UNITED STATES PATENT OFFICE.

EDWARD B. ALLEN, OF PORTLAND, MAINE, ASSIGNOR TO JAMES W. BROOKS,
TRUSTEE, OF CAMBRIDGE, MASSACHUSETTS.

NAIL-ASSORTING MACHINE.

SPECIFICATION forming part of Letters Patent No. 384,735, dated June 19, 1888.

Application filed August 22, 1887. Serial No. 247,551. (No model.)

To all whom it may concern:

Be it known that I, EDWARD B. ALLEN, of 5
Portland, county of Cumberland, and State of
Maine, have invented an Improvement in Nail-
Assorting Machines, of which the following de-
scription, in connection with the accompany-
ing drawings, is a specification, like letters on
the drawings representing like parts.

This invention has for its object to provide
10 a novel machine for automatically driving
headless nails into a flexible strip, preferably
paper, in order that the said nails may be read-
ily used in a heel-nailing or in any other usual
form of nailing-machine, the nails being driven
15 from the strip into the heel or other article to
be made.

In this invention I have provided means for
lifting, one at a time, the headless nails from
a nail-box and depositing the same in a chute,
20 said nail, if its head end is pointed in one di-
rection, taking one course into position under
the driver, and if its head end is in the other
direction taking another course and arriving
in position under the driver, the nail on its ar-
25 rival under the driver, no matter which course
taken by it, being delivered point downward
ready to be driven into the strip. The strip
is fed forward automatically after the driving
of each nail into it; but in case the nail is not
30 driven the feed does not operate; so it will be
seen the feed depends upon the insertion of a
nail into the strip at the last descent of the
driver.

The particular features in which my inven-
35 tion consists will be hereinafter described, and
pointed out in the claims at the end of this
specification.

Figure 1 in side elevation represents a ma-
chine embodying my invention, the neck and
40 guide for the paper and nail being partially
broken out. Fig. 1^a is a detail showing the
guides below the neck at the left of the dotted
line x^a, Fig. 1. Fig. 2 is an opposite side view
of Fig. 1, the driving-wheel being broken out
45 and the belt-wheel omitted; Fig. 3, an enlarged
vertical longitudinal section of part of the
frame-work and bearings in which the hollow
spindle reciprocates. Fig. 4 is a similar sec-
tion showing the hollow spindle in a different

position. Fig. 5 is a section below the irregu- 50
lar dotted line x, Fig. 1. Figs. 6 and 7 show
details to be referred to; Fig. 8, a section in
the line x^a, Fig. 1; and Fig. 9 shows a piece of
the paper strip with nails therein.

The frame-work a, of suitable shape to sus- 55
tain the working parts, has a main shaft, a',
driven in any usual way. This shaft has fast
upon it a belt-wheel, A¹⁰, and side by side two
cams, b c, the latter shown separately in Fig.
7, and a cam, a², the latter cam, as herein 60
shown, having a crank-pin, a³, which, by a
connecting-rod, a⁴, is joined to a stud, a⁵, on
an arm, a⁶, of a rock-shaft, a⁷, to which is se-
cured the oscillating hopper a⁸.

The hopper a⁸ has a slot, a⁹, (see Fig. 7,) 65
through which passes a rest, a¹⁰, grooved at its
upper end to receive in it a nail whenever in
the operation of the machine the left-hand end
of the hopper is in its most elevated position,
as in Fig. 1, that end of the hopper (see Fig. 70
8) having its floor somewhat reduced or cut
away to form a pocket, a¹¹, (see Fig. 8,) into
which will enter and remain one or more nails
when that end of the hopper is in its lowest po-
sition, that one of the nails which enters the 75
slot in the bottom of the said recessed portion
falls directly upon the top of the rest a¹⁰ and
remaining there while the left-hand end of the
hopper (see Fig. 1) is depressed. As soon as
the upper end of the nail lying on the rest a¹⁰ 80
arrives in the descent of the hopper above the
upper end of the guide a¹², secured to the
hopper, the said nail slides from the top of
the said rest and enters the upper enlarged end
85 of the chute a¹³, and as the hopper continues
to descend the nail deposited in the said chute
slides through it and through the chute a¹⁴ at
the lower side of the hopper, the said nail en-
tering, if its point is foremost, a conical open- 90
ing, c', made in a yoke, C, rigidly attached to
the frame-work a, and thereafter an opening
in the upper end of an expanding hollow spin-
dle, d. The left-hand end of the hopper, (see
Fig. 1,) as herein shown, has a head, a¹⁵, made
adjustable by a screw, a¹⁶, to regulate the 95
length of the pocket a¹¹ to the length of the
nail to be used.

The rest a¹⁰, herein shown as of segmental

shape, is loosely connected with the framework by a pin, a^{16} , a spring, a^{17} , attached to the hopper, acting against one edge of the rest to keep its opposite edge pressed closely against 5 the guide a^{10} .

The spindle d has attached to it by a screw, d' , (see Fig. 1,) a block, d^2 , having a stud, d^3 , (see Fig. 2,) over which is passed one end of a connecting-link, d^4 , jointed at its opposite 10 end by a stud, d^5 , to a slide-bar, d^6 , placed in a guideway, d^7 , secured to the framework, and adapted to be moved in a direction diagonal to the shaft d' , the said slide-bar having a stud which enters a cam-groove, d^8 , in the cam-disk c , (see Fig. 8 and dotted lines, Fig. 2,) the 15 rotation of the said cam-disk reciprocating the hollow spindle in the bearings $c' c^2$. The upper end of the spindle is slotted, so as to form a sort of spring-chuck, and the outer sides of the 20 arms so formed are outwardly beveled to co-operate with the beveled guide c' , so that when the spindle is drawn down, as in Figs. 1, 2, 3, its jaws will be closed, leaving but a small hole at its upper end for the entrance of any nail 25 the point of which is foremost, and thereafter, the point of the nail having entered the hole in the spindle, the spindle at its next rise will be expanded, permitting the nail t so entered to pass readily through the said spindle and 30 enter the guide-passage e in the neck E , shown as a metal block having two guide-passages, e and g' , both in communication with a driver-passage, e' , (see dotted lines, Fig. 1,) so that the driver e^2 , carried by the reciprocating cross-head e^3 , set in motion by the lever b^2 , pivoted 35 at b^3 and having a stud, b^4 , which enters the cam-groove b' of the cam b , before referred to, will act upon the head of the said nail and drive it into the paper or other strip f . (See 40 dotted lines, Fig. 2, and full lines, Fig. 9.)

In case the nail t emerging from the chute a^{13} should have its head end foremost, the said nail will drop into the bearing c' , just as before, while the spindle is in its lowest position; but 45 the head end of the nail is too large to enter the hole in the spindle, and consequently, as the spindle next rises with a quick blow, it strikes the head of the nail, knocks it point foremost out of the bearing c' , causing the said 50 nail to enter the auxiliary chute g point foremost, the nail descending in the said chute and entering the guideway g' , also in communication with the driver-passage e' . By this arrangement of chutes and the intervention of 55 the hollow spindle the nails are compelled to enter the passages e and g' point foremost, and consequently they arrive in the driver-passage point foremost.

The strip f will in practice be taken from a 60 suitable reel or cylinder, f' , and led through a folding-guide, f^2 , which will double the strip substantially at its center. The upper edges of the folded strip next pass into guiding-grooves at the upper end of a V-shaped guide, 65 f^3 , (see Figs. 1, 1^a, and 5,) against the bottom of which the said strip is held by a back piece,

f^4 , attached to the neck E , containing the passages e , g' , and e' , the said back piece having a depending slotted leg or tube, f^5 , which terminates substantially at the upper end of an 70 anvil, h , movement of which by the action of the end of the nail upon it determining whether or not the feeding mechanism, to be described, shall operate to feed the strip.

The cross-head to which the driver is attached is provided with an awl, n , which, as the driver descends, punches a hole in the paper strip to prepare it for the reception of a nail when the strip is next moved under the driver. 75

The anvil h , made as a sliding pin, extends through a hole in the bottom plate of the framework and rests upon one arm, h' , of the a lever, h^2 , pivoted at h^3 , the opposite end of the said lever having a pin, h^3 , which, when 80 the anvil is depressed by the pressure of a nail just driven into the strip, rises and acts upon a latch, h^4 , (see Fig. 5,) pivoted upon a carriage, h^5 , adapted to slide in guideways h^6 , attached to or forming part of the framework. This carriage is joined by a connecting-rod, h^7 , with a pawl-carrying arm, h^8 , having a pawl, h^9 , (see Fig. 6,) which engages a ratchet, h^{10} , secured to the shaft h^{12} , carrying the feeding-roll h^{13} , (see Figs. 1 and 5,) the latter being shown as corrugated to engage the strip and feed it intermittently. The opposite side of the strip is pressed against the supporting-roll m , mounted on a stud, m' , of an arm, m^2 , loosely held upon a post, m^3 , secured in the bed of the framework, the said post having attached to it a collar, m^4 , to which is attached one end of a spring, m^5 , the opposite or free end of the spring bearing against the arm m^2 , (see Fig. 2,) keeping the 95 said roll pressed toward the feeding-roll, the said two rolls gripping the strip at both sides. The cam-disk a^2 at its rear side has a groove, 100 a^2 , (see dotted lines, Fig. 1,) of suitable shape to receive the stud 21 of a lever, p , pivoted at p' , the said lever, whenever the latch h^4 is lifted, as described, coming against the said latch and moving the carriage to effect the movement of the feed-wheel; but if the said latch is not lifted the said arm in its vibration 105 will not effect the movement of the feed. 110

The pawl-carrying arm h^8 is provided with a guard, r , made as a spring-arm, the end of the said guard closing the open side of the open leg or tube f^5 while the nail is being 115 driven down through it by the driver, thus insuring a straight movement for the nail and insuring its contact with the upper end of the anvil.

United States Patents Nos. 348,091 and 125 348,092, heretofore granted to me, show an oscillating hopper somewhat like the one here-in shown.

The pawl-carrying bar is herein shown as restored to its normal position (shown in Fig. 130 5) by a spring, 25, secured to the said bar and to the guideway h^6 , the said spring becoming

operative when the lever p is disengaged from the latch h^4 , which occurs when the pressure is removed from the anvil h .

I claim—

5 1. In a nail-assorting machine, a movable hopper having a pocket at one end and a rest to enter said pocket, combined with a chute carried by the said hopper and into which each nail deposited upon the rest is delivered singly, 10 substantially as set forth.

15 2. The oscillating hopper, its guide, the chute connected to its upper side, and the chute extended from its lower side, combined with the rest adapted to work through a slot or pocket in the bottom of the said hopper, substantially as described.

20 3. The oscillating hopper a^x , having a slotted pocket or recess at one end for the retention of one or more nails, combined with an adjustable end plate to graduate the length of the recess to the length of the nail to be used, substantially as described.

25 4. In a nail-assorting machine, a beveled guide, and a hollow spindle having spring-jaws reciprocating in the said guide, combined with a chute to deliver the said nails to the said spindle, and with a block having a guide-passage in communication with the said spindle for the reception of such nails as pass point 30 foremost through the said spindle, substantially as described.

35 5. In a nail-assorting machine, a hollow spindle having spring-jaws, a beveled guide therefor, and a chute to deliver nails to the said spindle singly, combined with an auxiliary chute into which the said spindle rejects the nails delivered to it with the head end foremost, substantially as described.

6. In a nail-assorting machine, a reciprocating hollow spindle having spring-jaws, a bearing beveled at its upper end in which the said spindle slides, and a chute to deliver nails to the said spindle, combined with an auxiliary chute into which such nails as are delivered to the spindle head end foremost are rejected, the 45 nails delivered to the spindles point foremost being permitted to pass through the said hollow spindle at its next ascent, substantially as described.

7. In a nail-assorting machine, the guide to hold and present a strip of flexible material for the reception of nails, the nail-driver to drive nails point foremost into the said strip, and the movable anvil, combined with a strip-feeding mechanism, substantially as described, 50 and means to connect the said anvil and feeding mechanism, whereby the latter is set into operation by the movement of the anvil when acted upon by the point of the driven nail, substantially as described.

8. The vibrating lever, the carriage, its latch, and feeding mechanism, substantially as described, actuated by it, combined with a lever, h^* , and an anvil which is depressed intermittently by the point of the driven nail. 55

9. The guide f^3 and its open slotted leg or tube, and a spring-arm guard, combined with the anvil h , to operate substantially as described.

In testimony whereof I have signed my name 70 to this specification in the presence of two subscribing witnesses.

EDWARD B. ALLEN.
